(57) CLAIM

The ornamental design for a lint roller handle as shown and described.

DESCRIPTION

FIG. 1 is a perspective view showing the new design for a lint roller handle;

FIG. 2 is a front view thereof;

FIG. 3 is a back view thereof;

FIG. 4 is a left view thereof;

FIG. 5 is a right view thereof;

FIG. 6 is a bottom view thereof; and,

FIG. 7 is a top view thereof.

The broken lines immediately adjacent to the shaded areas depict the bounds of the claimed design, while all other broken lines are directed to environment. The broken lines form no part of the claimed design.

1 Claim, 4 Drawing Sheets
